UNITED STATES PATENT OFFICE.

WILLIAM S. MACHARG, OF CHICAGO, ILLINOIS.

DEVICE FOR EXTRACTING FLUID FROM SATURATED MATERIAL.

SPECIFICATION forming part of Letters Patent No. 777,796, dated December 20, 1904.

Application filed January 21, 1903. Serial No. 139,897.

To all whom it may concern:

Be it known that I, WILLIAM S. MACHARG, a citizen of the United States, residing at Chicago, in the county of Cook and State of Illinois, have invented a certain new and useful Improvement in Devices for Extracting Fluid from Saturated Material, of which the following is a specification.

My invention relates to devices for extracting fluid from saturated materials. An application of it is illustrated in the accompanying drawings, wherein—

Figure 1 is a side elevation of my apparatus with parts removed. Fig. 2 is a front view of the same with certain parts broken away. Fig. 3 is a plan view of certain parts of the machine. Fig. 4 is a plan view of a portion of the folder. Fig. 5 is a detail cross-section of the universal-joint device. Fig. 6 is a detail of the roller adjustment. Fig. 7 is a cross-section detail of the same. Fig. 8 is a detail of the belt-guide.

Like parts are indicated by the same letter in all figures.

25 A A are frame-pieces which together constitute a suitable frame for the proper support of the various parts.

B is a belt. I will describe the mechanism by reference to the parts with which this belt 30 is successively associated.

C is a belt-folder having a flat bottom C' suitably supported on the frame-pieces and having the two inwardly-folded side sections C² C³. As the belt emerges from the folder 35 it assumes the form indicated at B', where its two edges are carried past each other, so as to give a double fold of the belt. Immediately above the folder is a receptacle (not here shown) from which leads the funnel C⁴, which 40 opens into the folder between the side sections C² and C³ and discharges upon the middle of the belt B. Obviously, therefore, the belt is not only folded, but is folded so as to inclose the material within it. The belt is of 45 a material which is of such a nature as to permit the moisture to pass freely through it, and of course it can be made of any desirable material. The belt in its folded condition, which I will indicate by the letter B', now passes 50 around the wheel D, which has the diagonal

drainage-slots D' on its outer surface. This wheel D is mounted on a short shaft D², which is associated, by means of the universal joint D³, with the short shaft D⁴ and by means of the universal joint D⁵ with a similar shaft D⁶, 55 which carries a similar wheel D⁷. The shaft D⁶ is connected by the universal-joint device D⁸ with the short shaft D⁹. The universal-joint device D⁸ is more fully illustrated in Fig. 5, where there is shown a plate D¹⁰, mounted on a part A of the frame and carrying adjustable set-screws D¹¹ D¹², on which rests the yoke-piece D¹³. The shafts D² and D⁶ are journaled, by means of the spherical journals D¹³ D¹⁴, in this yoke, and each of these shafts is bifurcated at its outer end and provided with set-screws and cross-pins to engage the central block D¹⁴, so as to make the universal joint. The yoke D¹³ is adjustably secured, by means of the set-screws D¹⁵, to their associated slots, as 60 indicated in Fig. 3. The shaft D⁴ has the pinion D¹⁶, which engages the driving-pinion D⁷¹ on driving-shaft D¹⁸. By this means the two wheels D and D⁷ are driven simultaneously in the same direction and at the same speed. 65 Moreover, while in the drawings they are shown as rotating on the same axis it is obvious that their relative positions may be changed by means of the adjustments and the universal joints. This may become necessary 70 under certain conditions because of the organization of the apparatus which involves the running of the belt from one wheel to another. The belt B' after passing under the wheel D encounters a compression-roller E, 75 which is mounted in the arms E' E', which are secured together on a pivot-bar E², journaled in the standards E³, which are mounted on the frame-pieces. The bars E' E' are shaped as shown in Fig. 1, each with a lower portion E⁴, 80 like a scale-beam, associated with a movable weight E⁵, whereby the pressure of the roller E against the traveling belt B' may be varied. Each of the bars E⁴ has a rear hook-like projection E⁶, which receives the weight E⁵ and 85 holds the parts in position, the roller free from the wheel and belt when such parts are in the positions indicated in dotted lines in 90 Fig. 1. The belt B' now passes around and entirely over the wheel D and then into the 95 100

guide F and thence over the tension-wheel G. This tension-wheel is mounted in the sliding frame G', which is in turn supported in and mounted on the frame G², which is affixed to the frame-piece A. To the forward end of the frame G' is attached the rope G³, which runs over the idler G⁴ and on which is mounted the weight-disks G⁵, so that the tension-wheel G has applied to it a variable tension 5 to keep the belt at any desired tension on the wheel D. When the belt passes over this idler tension-wheel G, it passes into another fixed guide, F'. The tension-wheel G is inclined, as shown, and thus the direction of the belt is changed, and it now passes under the wheel D⁷ and around the same under a compression device, which is a duplicate of that previously described as associated with wheel D. The belt as it passes over the top of wheel 10 D⁷ enters an unfolding device J, which may, however, be a duplicate of the folding device in the reverse position. This obviously unfolds the belt or brings it into its original unfolded condition. This unfolding or opening 15 of the belt takes place at the point indicated in Fig. 1, at the forward part of the unfolding device J, and the contents, being the material which was to be freed of moisture, is discharged into the receptacle J' below. In 20 order that the belt may more perfectly be cleaned, it may engage as it passes out of the unfolder a rotary brush or other scraper or cleaner J². The belt is now to be guided back to the folding device C. This is effected by 25 the frames and group of rollers which I will now describe.

K is a frame-piece, shaped somewhat as indicated in Figs. 1 and 2, associated with a similar frame-piece, and both of these frame-pieces are attached to the frame proper. 30 Mounted in these frames are rollers K', K², K³, K⁴, K⁵, K⁶, and K⁷, inclined as shown, so as to guide the belt properly. The roller K⁴ is preferably mounted in slots in the frames 35 and associated with a bail K⁸, to which is secured the cord K⁹, which runs over the idler K¹⁰ on the standard K¹¹ and to which is attached the weight-disks K¹², so that by adjusting the weights a variable tension can be 40 put upon the roller K⁴ to keep a suitable tension on the belt. It may be desirable to have these rollers adjustable, and hence I have shown in Figs. 6 and 7 an adjustable bearing. In the frame K at the proper point is 45 inserted a disk L, held in position by the ring L' and adapted to be locked in any desired position by the set-screw L². Across the middle portion of this disk is formed the slot L⁴, in which is mounted the slide L⁵, being held 50 in position by the flange L⁶ and the piece L⁷. This slide L⁵ is held in position by the set-screw L⁸. Thus by turning the disk to any desired position the position of the slot can be varied, and by moving the slide in the slot the 55 other end of the roller can be adjusted.

In Fig. 8 I have shown a modification of the guides for the folded belt. M is the flat bottom of such a guide. N is one of a series of rollers which may be journaled in the sides M' of such guide. These guides have inwardly-extending upper edges M², and thus the folded belt B' is held in position, carrying the material O from which the moisture is to be extracted. 70

It is obvious that what I have described is 75 to be taken as diagrammatic in an important sense or as merely illustrative of a single means for utilizing my invention, and I do not wish to be understood as intending to limit myself to the particular form and arrangements, proportions, and shapes of the several parts. To make more evident what I mean by this suggestion, I will point out some of the obvious changes which could be made. The important characteristics of my device is 80 still present even though the belt be carried over but one of the large wheels, and such large wheel may consist of a wheel with a flat surface or curved surface, or it might consist of a frame with a series of rollers. The power 85 can be applied in any desired manner to drive the belt, and any desired guiding and controlling and tension devices can be substituted for those I have shown without materially departing from my invention. The belt can 90 be made of any desirable material, and it is possible that the material could be carried up and around a properly-constructed wheel 95 without actually folding over the edges of the belt. 100

In Fig. 1 I have shown in a diagrammatic manner a detail of a device for wiping or rubbing off the water from the outside of the belt. In many instances the belt will discharge the greatest portion of the liquid on 105 its outside, and to facilitate the removal of this liquid I provide the sponge-like belt P, which runs over the rollers P' P² P³ P⁴ and between the rolls P⁷ and P⁸ of a wringer. The sponge belt is tightened, so as to keep it down 110 upon the belt B', by means of the weight P⁹ and the roller P⁴, which latter is drawn upwardly by means of the cord P¹⁰, which travels over the pulley P⁵ and thence to the weight P⁶. Of course these parts can be greatly altered, and what is shown is to be taken simply as diagrammatic. A brush or some other kind of device for taking off the liquid might be substituted. The device, broadly speaking, may be considered as a liquid-remover, 115 and the specific form shown might be described as an absorbent liquid-remover. This device may be driven by a separate power or by connection with the driving parts which drive the wheel or may be driven by friction from its engagement with the wheel. The belt may be in part of impervious material— 120 as, for example, that portion of the belt which lies next to the wheel-like structure might be impervious. 125 130

The use and operation of my invention are as follows: The material from which liquid is to be extracted can be fed into the belt, whereupon by the motion of the belt it is carried around, preferably inclosed in the folds of the belt, over a surface against which it is pressed by the tension applied to the belt, so that the liquid tends to flow from the material within the folds of the belt. In the form shown this liquid if pressed out through the inside of the belt passes into the diagonal grooves and may run off to any desired receptacle. It is applicable to a case in which the liquid to be extracted is the thing to be preserved or to a case where the material freed from the liquid is the thing desired or to a case where both products are valuable, and therefore any desired devices for receiving either the liquid or the more solid material can be supplied. In the particular form of machine which I have illustrated the belt is designed to travel twice over such wheels, and therefore it becomes necessary to change the direction of travel of the belt. Hence it has been necessary for me to invent certain devices for this purpose. Obviously the tension of the belt must vary according to conditions. Therefore in addition to devices for changing the direction of travel of the belt or the relative position of the parts over which it travels I have invented and supplied means for varying the tension of the belt at different points along the line of its travel. I have also supplied means for folding the belt and for unfolding it at the necessary points. The material charged with liquid is emptied upon the belt, inclosed within the folded belt, carried about the first wheel, which I will call the "extracting-wheel," then carried off to an idler arranged to change its direction, and then carried about another extracting-wheel, then directed through an unfolding device which unfolds the belt and empties its contents, then carried along a direction-changing device until it again enters the folding device, after having received a new charge of material from which liquid is to be extracted. The liquid extracted may pass through the outer surface of the belt when the belt is on the extracting-wheel, and it also may pass through the inner portions of the belt which lie between the wheel and the material. It is perhaps at this latter point that most of the liquid will be extracted and will be carried away through the diagonal grooves when there is a relatively small amount of liquid in the material.

I have used the words "tension-extractor" to indicate my belt, as the same is a device by means of which the fluid is extracted by tension and not by pressure in the ordinary sense of the latter term.

It will be observed in my device that there is what I will call a "free" extraction of the fluid—that is, an extraction of the fluid at a

point or points where pressure is applied to the belt while it is, so to speak, free or while it is in contact with one surface only and not being passed between rolls. There is therefore an extended surface of extraction as distinguished from a case where the extraction of the fluid is brought about, for example, by two opposed rolls. 7c

I claim—

1. In a device for extracting fluid from materials the combination of a porous belt with means for applying the material thereto and a wheel-like structure about which said belt travels and a tension device to apply sufficient pressure to the belt to cause the liquid to pass through the belt. 75

2. In a device for extracting fluid from materials the combination of a porous belt with means for supplying the material thereto and means for folding the belt upon such material 85 so as to inclose it and a wheel-like structure about which said belt travels and a tension device to apply sufficient pressure to the belt to cause the liquid to pass through the belt.

3. In a device for extracting liquid from materials the combination of a porous belt with means for supplying the material thereto and a belt-folder which folds the edges of the belt over upon each other so as to inclose the material and a tension device to apply sufficient 95 pressure by tension to the belt so as to cause the liquid to pass through the same. 90

4. In a device for extracting liquid from materials the combination of a porous belt with means for supplying the material thereto and 100 a belt-folder which folds the edges of the belt over upon each other so as to inclose the material and a tension device to apply sufficient pressure by tension to the belt so as to cause the liquid to pass through the belt, said tension device containing a wheel-like structure 105 about which such belt passes.

5. In a device for extracting fluid from materials, the combination of a porous folded belt by which the material is carried, wheels over 110 which it travels, said belt in a folded condition while traveling over one of said wheels, means for varying the distance between the axes of the wheels to vary the tension on the belt and thus extract the fluid in connection with the 115 wheel over which it passes while in its folded condition.

6. In a device for extracting fluid from materials, the combination of a porous folded belt by which the material is carried, wheels over 120 which it travels, said belt in a folded condition while traveling over one of said wheels, and means for applying tension to the belt and thus extracting the fluid in connection with the wheel over which it passes while in its folded 125 condition.

7. In a device for extracting fluid from materials, the combination of a porous belt by which the material is carried with a wheel over which it travels, and a liquid-take-up device, 130

which bears upon the belt and takes up the liquid extracted therethrough.

8. In a device for extracting fluid from materials, the combination of a porous belt by 5 which the material is carried with a wheel over which it travels, and a liquid-take-up device, which bears upon the belt and takes up the liquid extracted therethrough, said liquid-take-up comprising a sponge-like body to bear 10 upon the belt.

9. In a device for extracting fluid from materials, the combination of a porous folded belt by which the material is carried, and means 15 for carrying the belt along and deflecting it from a straight line so as to tighten the exterior fold of the belt and thus extract the fluid from the material therein.

10. In a device for extracting fluid from materials, the combination of a porous folded belt 20 by which the material is carried, wheels over which it travels, and means for applying pressure to the material by the tension of the belt to extract the fluid therefrom through the belt.

11. In a device for extracting fluid from materials, the combination of a belt-like body which carries the material, a series of wheel-like structures over which the belt travels, a 25 guide-roller, a guide-frame over which the belt travels, and a tension device to tighten the belt and thus extract the fluid.

12. In a device for extracting fluid from materials, the combination of a belt-like body which carries the material, a series of wheel-like structures over which the belt travels, a 35 guide-roller, a guide-frame over which the belt travels, the guide-roller inclosed within the guide-frame, and a tension device to tighten the belt and thus extract the fluid.

13. In a device for extracting fluid from materials, the combination of a belt-like body which carries the material, a series of wheel-like structures over which the belt travels, a 40

guide-roller, a guide-frame over which the belt travels, and a tension device for tightening 45 the belt and thus extracting the fluid associated with the guide-frame.

14. In a device for extracting fluid from materials, the combination of a belt-like body which carries the material, a series of wheel-like structures over which the belt travels, a 50 guide-roller, a guide-frame over which the belt travels, and a tension device for tightening the belt and thus extracting the fluid associated with the guide-roller. 55

15. In a device for extracting fluid from materials, the combination of a belt-like body which carries the material, a series of wheel-like structures over and around which the belt travels, a pressure device for applying 60 pressure to the belt where it passes over the wheel without external applications to such belt whereby the fluids from the material in the belt are extracted.

16. A device for extracting fluid from materials, comprising a belt-like body to contain such materials with a wheel about which it 65 travels so as to have an extended surface of contact therewith, and a pressure device to apply pressure to the belt at such surface of 70 contact without engaging the outer surface of the belt.

17. A device for extracting fluid from materials comprising a belt-like body to contain such materials with a wheel about which it 75 travels so as to have an extended surface of contact therewith and a tension device to apply pressure to the belt along such extended surface of contact so that the extraction takes place simultaneously over all parts of an extended surface. 80
